(57) **CLAIM**

The ornamental design for an instrument panel register, as shown and described.

DESCRIPTION

FIG. 1 is an isometric view of a front side of the instrument panel register in a fully open condition;

FIG. 2 is an isometric view of a rear side thereof;

FIG. 3 is a side view of a first side thereof;

FIG. 4 is a front view thereof;

FIG. 5 is a side view of a second side thereof;

FIG. 6 is a rear view thereof;

FIG. 7 is a top view thereof;

FIG. 8 is a bottom view thereof;

FIG. 9 is an isometric view of the instrument panel register in the fully open condition in an alternative position;

FIG. 10 is an isometric view of the instrument panel register in the fully open condition in another alternative position;

FIG. 11 is an isometric view of the instrument panel register in the fully open condition in another alternative position;

FIG. 12 is an isometric view of the front side of the instrument panel register in a fully closed condition;

FIG. 13 is a front view of the instrument panel register in the fully closed condition; and,

FIG. 14 is an isometric view of the instrument panel register shown at a greatly reduced scale installed in an instrument panel.

The broken lines showing of environment are for illustrative purposes only and form no part of the claimed design.
